UNITED STATES PATENT OFFICE.

GEORGE TAYLOR FOSSELLE, OF MUSKEGON, MICHIGAN, ASSIGNOR TO AUSTIN MACHINERY CORPORATION, OF MUSKEGON, MICHIGAN, A CORPORATION OF VIRGINIA.

POWER SHOVEL.

Application filed January 21, 1927. Serial No. 162,593.

This invention relates to improvements in power shovels of that type in which the derrick and shovel-actuating mechanism are carried by an upper deck pivotally mounted 5 on a lower deck that is fixed with relation to the carriage or other support of the machine. In such devices a circular gear and an annular track are mounted between the two decks concentric to the pivotal connection and fixed to the lower deck. On the 10 under side of the upper deck are mounted rollers to travel on the annular track to transmit the load of the upper deck to the lower deck. A shaft is journalled at its upper part in a vertical bearing fixed on the upper deck and is driven by a gear connection with a suitable motor. This shaft has a pinion fast on its lower end meshing with the circular gear so that rotation of the shaft 15 causes the pinion to travel around the circular gear and through the shaft connection the upper deck is turned to and fro according to the rotational direction of the pinion. The upper deck carries a considerable 20 load,—the weight of the shovel, its support and actuating mechanism and of the material being handled—the inertia of which must be overcome in starting a turning movement of the upper deck; also, when in motion, 25 the loaded upper deck accumulates considerable momentum, the energy of which must be absorbed when the turning movement is stopped. In overcoming the inertia of the loaded deck in starting and in absorbing 30 the energy of the momentum when stopped, particularly when the drive is suddenly reversed, excessive strain is thrown on the actuating mechanism and the connected parts and the machine is racked and jarred. 35 When an explosive engine is employed as the source of power, with its sudden application of power, the strain and the force of the shocks imparted to the machine are very 40 much amplified.

In the instant invention the annular track and the circular gear are mounted between the two decks so as to be relatively rotatable to a limited extent, the track being fixed to the lower deck and the circular gear 45 being movably mounted thereon. Interposed between the track and gear is a spring mechanism to absorb the shock of starting and stopping the upper deck and thereby relieves the machine of the strain that would 50 otherwise be imparted to it if both the track

and gear should be fixed to the lower deck. Also, the energy of the spring mechanism compressed by absorbing the momentum of the load in stopping the same, is utilized 55 to assist the motor in overcoming the inertia of the load in starting the same in the opposite direction. The particular mechanism employed in carrying out the invention is described in detail hereinafter, pointed out in the appended claims and illustrated by 60 the accompanying drawings.

In the accompanying drawings, in which similar reference characters designate corresponding parts:

Figure 1 is a plan view of the annular track and the circular gear mounted in their 65 related positions.

Figure 2 is a sectional view on the line 2—2 of Fig. 1.

Figure 3 is an enlarged detail view showing in horizontal section of a part of the track and gear and one of the interposed spring mechanisms.

Figure 4 is a sectional view on the line 70 4—4 of Fig. 1.

Figure 5 is a sectional view on the line 5—5 of Fig. 3.

Figure 6 is a transverse sectional view 75 through the pivotal center of the decks and the vertical bearing for the shaft carrying the pinion for driving the upper deck.

Referring to the drawings in detail, 10 designates the lower deck of the machine and, as shown, it forms a fixed part of the chassis 80 of the tractor, carrying the excavating mechanism. Pivottally mounted on the lower deck is the upper deck 11 having a central bearing 12 journaled on a hub 13 integral with the conical cap 14 bolted to the lower deck. In an annular recess in the upper end 85 of the hub 13 is seated a ring 15 and threaded on the ring is a collar 16 forming a thrust contact for the upper end of the bearing 12 of the upper deck. This thrust contact serves to hold the upper deck against any 90 tendency it might have to move upwardly on the hub.

Secured on the lower deck 10 in a horizontal position is the annular track 17 on which travel the rollers 18 carried by a 95 frame pivoted to the under side of the upper deck 11. On the upper deck, immediately above the rollers, are mounted the shovel boom (not shown) and other heavy parts of the machine, so that the heaviest part of the 100

load on the upper deck is carried by the rollers and transmitted to the annular track.

Projecting from the inner face of the annular track 17 is the horizontal flange 19. 5 Riding on this flange and fitting within the annular track is the circular gear 20 having internal teeth. On the upper part of the outer faces of the circular gear is the flange 21 riding on the shoulder 22 on the inner 10 face of the track. These engagements of the gear with the track serve to maintain the two parts in their related horizontal position during the travel of the gear within the track.

15 Meshing with the internal teeth of the circular gear 20 is the pinion 23 fast on the lower end of the vertical shaft 24 journaled in the vertical bearing 25 integral with the upper deck 11. Means (not shown) are 20 provided for rotating the shaft in either direction. When the shaft is rotated the pinion travels around the circular gear and thereby the upper deck is rotated. At intervals, preferably four in number, lugs 26 25 project from the periphery of the circular gear into opposite recesses 27 in the inner wall of the annular track. The width of the lug is somewhat less than the length of the recess so that when the circular gear is 30 turned in either direction the lug engages the wall at either end of the recess and thereby limits the rotative movement of the circular gear with relation to the annular track. The several lugs are of the same arcuate 35 length, as are the recesses in which they travel, and the relative positions of the lugs and their engaged recesses are such that all the lugs simultaneously reach the limits of their travel in their respective recesses. 40 Consequently, the strain imparted to the circular gear by the pinion in starting and stopping the rotation of the upper deck is simultaneously transmitted through all the lugs to the engaged annular track.

45 The casing of the annular track 17 provides an annular bearing for the circular gear 20 and the lugs or abutments 26 of the gear having limited travel in the opposite recesses 27 in the track casing provide a 50 series of loose interlocks between the gear and bearing members. These interlocks with loosely engaging parts operate to transmit to the bearing member the thrust imparted to the gear member by the drive and 55 permit limited play between the two members, the play being restricted to the travel of the abutments in the opposite recesses.

Integral with the annular track 17 and on opposite sides of each of the lugs 26 are 60 the housings 28. Each housing has an enlarged cylindrical bore 29 in its outer part and a reduced rectangular guideway 30 through its inner part, the longitudinal axes 65 of the bore and guideway being coincident with the longitudinal axis of the housing.

The longitudinal axis of the housing is approximately normal to the side of the lug or abutment 26 opposite to the inner end of the housing, and the angle of the intercepting longitudinal axes of the opposite housings approaches 180 degrees. 70

Slidable in each housing 28 is a stop-bolt 31, tubular at its outer part 32 and rectangular in cross-area at its inner part 33 to fit the guideway 30. At an intermediate part 75 of the stop-bolt, adjacent the inner end of the tubular part 32, is a flange 34, against which is seated the inner end of the coiled spring 35 loosely fitting in the cylindrical bore 29 of the housing and around the tubular outer part 32 of the stop-bolt. In the outer end of the housing is the nut 36 secured in place by pins 37 passing through the nut and the wall of the housing. 80

85 Threaded through the nut 37 is the adjusting pin 38 in axial alignment with the housing. The inner end of the adjusting pin enters the tubular outer part 32 of the stop-bolt and forms a guide for the outer end of the bolt. A lock-nut 39 holds the adjusting pin in its adjustments. On the adjusting pin, inside of the nut 36, is the shoulder 40 against which seats the washer 41 engaging the outer end of the spring 35. By adjusting the pin 38 the compression of the spring between the washer 41 and the flange 34 can be regulated to vary the resistance offered to the outward movement of the stop-bolt 31. The washer 41 engaging the shoulder 40 also forms a stop to limit the outward movement of the stop-bolt, and the position of the washer can be varied by turning the adjusting pin. The inward movement of the stop-bolt is limited by the flange 34 striking the shoulder 42 at the inner end of the cylindrical bore of the housing. 100

105 The rotative movement of the circular gear 20 with relation to the fixed annular track 17 is limited by the play of the abutments 26 in their respective recesses 27 and also by the stop-bolts 31 engaging the abutments. The play of the abutments in their recesses provide the extreme limits of the movement of the gear and between these 110 limits the movement can be restricted to any required extent by adjusting the stop-bolts. Under certain conditions of work it is desirable to operate the machine with the maximum relative play between the circular gear and the annular track and under other conditions a more restricted relative play is an advantage; also, different work conditions require different degrees of compression for the thrust of the stop-bolts. 115

120 Preliminary to the operation of the machine, the pins 38 are adjusted in their respective nuts 36 to limit the movement of the stop-bolts and also to compress the springs 35 when the deck is started. When 125 130

the rotation of the deck is initially started, for an instance by the travel of the pinion 23 in the direction indicated by the arrows *c*, Fig. 3, the drag of the pinion imparts a 5 thrust to the circular gear 20 that tends to turn the gear in relation to the annular track 17 in a direction contrary to that indicated by the arrows *c*. This movement of the circular gear with relation to the annular 10 track, through the engagement of the lugs 26 with the stop-bolts 31, compresses the springs in the series *a*. By first compressing this series of springs the inertia of the load is gradually overcome with a resulting 15 starting of the turning movement of the upper deck. After the inertia of the load is overcome and the rotary movement of the deck started, the compressed springs expand again and through the thrust of their respective stop-bolts 31 against the lugs 26 the circular gear is turned to position the lugs about midway of their respective recesses 27 and the cushioning effect between the gear and the track is maintained. When 20 the shovel is positioned and the application of power to the shaft 24 is discontinued, the shaft and pinion 23 act to stop the rotary movement of the upper deck. When this happens the momentum of the load is transmitted to the circular gear to be absorbed by the other series *b* of the springs through the action of their respective stop-bolts 31 impinging on the lugs 26 on the sides thereof opposite to those engaged by the stay-bolts of the springs of the series *a*. In this 25 way the inertia of the load is gradually overcome in starting a turning movement of the upper deck and the momentum of the load is gradually absorbed in stopping the turning movement, so that the machine is relieved of much of the strain incident to the starting and stopping and the shocks and jars are avoided. This is particularly so 30 during the sudden reversal of the drive occasioned by a rapid swinging to and fro of the shovel.

What I claim is:

1. In a power-shovel, the combination with a lower deck, of an upper deck pivotally mounted on the lower deck, an annular member fixed on the lower deck, a circular gear movable on the lower deck and provided with an abutment having restricted play in a recess in the annular member, stop-bolts 50 slidable in the annular member and impinging on opposite sides of the abutment, springs normally pressing the stop-bolts against the abutment to oppose turning movement of the circular gear with relation to the fixed member, and a gear drive mounted on the upper deck and engaging the circular gear to rotate the upper deck.

2. In a power-shovel, the combination with a lower deck, of an upper deck pivotally mounted on the lower deck, an annular

member fixed on the lower deck, a circular gear movable on the lower deck and provided with an abutment having restricted play in a recess in the annular member, 55 housings in the annular member on opposite sides of the abutment, stop-bolts slidable in the housings and impinging on opposite sides of the abutment, springs in the housings normally pressing the stop-bolts against the abutment to oppose turning movement of the circular gear with relation to the annular members, adjustable means mounted 60 in the housings for regulating the pressure of the springs on the stop-bolts, and a gear drive mounted on the upper deck and engaging the circular gear to rotate the upper deck.

3. In a power-shovel, the combination with a lower deck, of an upper deck pivotally mounted on the lower deck, an annular member fixed on the lower deck, a circular gear concentric with the annular member and movable on the lower deck, said gear being provided with an abutment having restricted play in a recess in the annular member, 65 housings in the annular member on opposite sides of the abutment, stop-bolts slidable in the housings and impinging on opposite sides of the abutment, springs in the housings normally pressing the stop-bolts against the abutment to oppose turning movement of the circular gear with relation to the annular member, adjustable means in the housing for regulating the play of the 70 stop-bolts with relation to the abutment, and a gear drive mounted on the upper deck and engaging the circular gear to rotate the upper deck.

4. The combination with a fixed annular member, a circular gear concentric with the annular member and rotatable with relation thereto, an abutment on the circular gear having limited play in a recess of the annular member, a housing forming part of the annular member, a stop-bolt movable in the housing and impinging on the abutment, a coiled spring within the housing and engaging at one end the stop-bolt, and means adjustable in the housing and engaging the other end of the coiled spring for regulating 105 the pressure of the spring on the stop-bolt.

5. The combination with a fixed annular member, a circular gear concentric with the annular member and rotatable with relation thereto, an abutment on the circular gear having limited play in a recess of the annular member, a housing forming part of the annular member, a tubular stop-bolt movable in the housing and impinging at its inner 110 end on the abutment, said stop-bolt having a flange at an intermediate part, a pin adjustable in the outer end of the housing and entering the tubular stop-bolt, a washer seated on the pin within the housing, and a coiled spring within the housing around the 115

stop-bolt and compressed between the washer on the adjusting pin and the flange on the stop-bolt, adjustment of said pin operating to regulate the compression of the spring to vary the thrust of the stop-bolt against the abutment.

6. In a power-shovel, the combination with a lower deck, of an upper deck pivotally mounted on the lower deck, an annular bearing fixed on the lower deck concentric to the pivotal mounting of the upper deck, a circular gear journaled in the annular bearing, an interlock having loosely engaging parts connecting the circular gear and annular bearing to permit restricted play between the same and said interlock operating to provide positive engagement between the gear and bearing at the limits of their restricted relative play to transmit the thrust 20 of the circular gear to the annular bearing, a gear drive mounted on the upper deck and engaging the circular gear to rotate the upper deck, and resilient means operating to transmit the thrust of the circular gear to 25 the annular bearing during the relative play of the gear and bearing permitted by the interlock.

7. In a power-shovel, the combination with a lower deck, of an upper deck pivotally mounted on the lower deck, an annular bearing fixed on the lower deck concentric to the pivotal mounting of the upper deck, a circular gear journaled in the annular bearing, an abutment on one of said gear 30 and bearing members and loosely engaging an opposite recess in the other member to permit restricted relative play between said members, said abutment operating to provide positive engagement between said members at the limits of their restricted relative play to transmit the thrust of one member 35 to the other, a gear drive mounted on the upper deck and engaging the circular gear to rotate the upper deck, and resilient means operating to transmit the thrust of one of 40 said members to the other during the relative play of the members permitted by the abutment.

8. In a power-shovel, the combination with a lower deck, of an upper deck pivotally mounted on the lower deck, an annular bearing fixed on the lower deck concentric to the pivotal mounting of the upper deck, a circular gear journaled in the annular bearing, an abutment on the circular gear 50 loosely engaging an opposite recess in the annular bearing to permit restricted play of the gear relative to the gearing, said abutment operating to provide positive engagement of the circular gear with the annular bearing at the limits of the restricted play of the circular gear to transmit the thrust of the gear in either direction to the bearing, a gear drive mounted on the upper deck and engaging the circular gear to rotate the upper deck, and resilient means operating to transmit the thrust between the gear and the bearing during the relative play of the members permitted by the abutment.

9. In a power-shovel, the combination with a lower deck, of an upper deck pivotally mounted on the lower deck, an annular bearing fixed on the lower deck concentric to the pivotal mounting of the upper deck, a circular gear journaled in the annular bearing, an abutment on the circular gear 70 loosely engaging an opposite recess in the annular bearing to permit restricted play of the gear relative to the bearing, said abutment operating to provide positive engagement of the circular gear with the annular bearing at the limits of the restricted play of the circular gear to transmit the thrust of the gear in either direction to the bearing, a gear drive mounted on the upper deck 75 and engaging the circular gear to rotate the upper deck, and resilient mechanism mounted on the annular bearing and including a spring-pressed bolt impinging on the circular gear to transmit the thrust of the circular gear to the annular bearing during the restricted play of the gear relative to the bearing permitted by the abutment.

In testimony whereof I affix my signature.

GEORGE TAYLOR ROSSELLE.
